CLAIM

I claim the ornamental design for cylindrical filter element, as shown and described.

DESCRIPTION

The broken line showing of environmental structure in FIGS. 1–12 is for illustrative purposes only and forms no part of the claimed design.

Characteristic features of the design include the larger open areas compared to the area covered by the spiral wrap and the edge pattern of the two beads of adhesive which are visible through the spiral wrap.
